US0D1027027S

(12) **United States Design Patent** (10) Patent No.: **US D1,027,027 S**
(45) Date of Patent: ** May 14, 2024

(54) **DIGITAL MULTIFUNCTION PRINTER**

(71) Applicant: **FUJIFILM Corporation**, Tokyo (JP)

(72) Inventors: **Kazuyuki Ogi**, Tokyo (JP); **Masaaki Takenouchi**, Tokyo (JP)

(73) Assignee: **FUJIFILM CORPORATION**, Tokyo (JP)

(**) Term: **15 Years**

(21) Appl. No.: **29/855,302**

(22) Filed: **Sep. 30, 2022**

Related U.S. Application Data

(63) Continuation of application No. 29/739,219, filed on Jun. 23, 2020.

(30) **Foreign Application Priority Data**

Dec. 26, 2019 (JP) 2019-029011
Dec. 26, 2019 (JP) 2019-029013

(57) **CLAIM**

The ornamental design for a digital multifunction printer, as shown and described.

DESCRIPTION

FIG. 1 is a perspective view of a digital multifunction printer showing our new design;

FIG. 2 is another perspective view of the digital multifunction printer;

FIG. 3 is a front view of the digital multifunction printer;

FIG. 4 is a rear view of the digital multifunction printer;

FIG. 5 is a plan view of the digital multifunction printer;

FIG. 6 is a bottom view of the digital multifunction printer;

FIG. 7 is a right side view of the digital multifunction printer; and,

FIG. 8 is a left side view of the digital multifunction printer.

The broken lines shown in the drawings represent portions of the digital multifunction printer that form no part of the claim.

1 Claim, 8 Drawing Sheets
